US00D493225S1

(12) **United States Design Patent** (10) Patent No.: **US D493,225 S**
(45) Date of Patent: **** Jul. 20, 2004**

(54) **IMPLANT**

(75) Inventors: **Peter Pal Varga**, Budapest (HU);
James W. Ogilvie, Minneapolis, MN
(US)

(73) Assignee: **Ortho Development Corporation**,
Draper, UT (US)

(**) Term: **14 Years**

(21) Appl. No.: **29/185,044**

(22) Filed: **Jun. 19, 2003**

Related U.S. Application Data

(63) Continuation of application No. 10/358,103, filed on Feb. 3, 2003, now abandoned, which is a continuation of application No. 10/188,281, filed on Jul. 1, 2002, now abandoned, which is a continuation of application No. 09/592,072, filed on Jun. 12, 2000, now Pat. No. 6,579,318.

(51) LOC (7) Cl. **24-03**

(52) U.S. Cl. **D24/155**

(58) Field of Search **D24/155; 606/61,
606/69; 604/500; 623/17.16, 17.15**

(57) **CLAIM**

We claim the ornamental design for an implant, as shown and described.

DESCRIPTION

FIG. 1 is a perspective view thereof;
FIG. 2 is a top view thereof;
FIG. 3 is a bottom view thereof;
FIG. 4 is a right side view thereof;
FIG. 5 is a left side view thereof;
FIG. 6 is a front view thereof;
FIG. 7 is a rear view thereof;
FIG. 8 is a perspective view of a second, alternative embodiment of the implant of FIG. 1;
FIG. 9 is a top view of the implant of FIG. 8;
FIG. 10 is a bottom view of the implant of FIG. 8;
FIG. 11 is a right side view of the implant of FIG. 8;
FIG. 12 is a left side view of the implant of FIG. 8;
FIG. 13 is a front view of the implant of FIG. 8; and,
FIG. 14 is a rear view of the implant of FIG. 8.

The portions of the figures shown in broken lines are for illustrative purposes only and form no part of the claimed design pertaining to the particular embodiment showing the broken lines.
